UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

MACHINE FOR FEEDING AND DRIVING LACING HOOKS AND THE LIKE.

Application filed December 9, 1922. Serial No. 605,832.

This invention relates to machines for setting lacing hooks or the like in leather or other sheet material, and more particularly provides a new and improved type of hook setting machine including a hopper for holding a collection of hooks in random relation, a hook-driving spindle at a point remote from the hopper, and sorting and conveying means for such hooks intermediate hopper and spindle.

As will be understood from what follows, the invention is of particular value and has preferred application in connection with a machine for setting lacing hooks, in which machines it has been common to employ a pick-up wheel rotated through such collection and provided with a plurality of transverse openings the edges of which openings serve to collect the hooks by engaging the hooked portions of the lacing hook, and in which machines it is well-known to employ a gravity raceway to receive the hooked portions of the lacing hooks as the latter are discharged from the openings in the pick-up wheel.

It is the prime object of this invention to provide in such lacing hook setting machines an apparatus for insuring the feeding of one hook at a time to the driving spindle and for insuring the accumulation of a column of sorted hooks adjacent the spindle for such feeding. The invention thus involves the provision of a novel group of cooperator mechanisms. The first of such mechanisms is a new and improved pick-up wheel necessarily a part of the complete new combination of all such mechanisms, as the chief characteristic of this new wheel is that a large enough number of the picked-up hooks will be positively retained on the wheel for certain delivery to the upper end of the raceway, as to insure that a surplus column of sorted hooks at the lower end of the raceway will always be for cooperation with the second of the cooperator mechanisms of the combination. In connection with the new function of the present pick-up wheel as just described, it will be understood that the previous lack of such a wheel has been serious, due to the excessive vibrations of the entire hook-setting machine dur-

ing operation. So difficult is it to overcome entirely the effects of such vibrations in causing the pick-up wheel to lose a certain proportion of the picked-up hooks before the latter are discharged to the upper end of the raceway, that the frank admission is made here without apology that the new pick-up wheel, as important an advance over the prior art as the same is thought to be, loses a certain proportion of the picked up hooks; indeed, the fact of such loss, small as it is compared to previous losses, is what brings necessarily into the new combination the second of the cooperator mechanisms above mentioned. Said second of the new mechanisms includes means automatically predeterminedly to engage the lowermost hook in the raceway and forcibly thrust said hook directly into a special receiving recess on the bottom of the spindle, such means also preferably at the same time holding the remaining hooks in the raceway away from the spindle. Only by the combined provision of the new pick-up wheel and the new means just mentioned, it will be seen, may dependence be placed on the spindle-recess receiving a single hook on the retraction of the spindle after each driving stroke thereof, because while the new pick-up wheel may absolutely be depended on to maintain a surplus of hooks in the raceway, such surplus is not always established as a column of sufficient height and weight to insure that the lowermost hooks will pass by gravity from the lower end of the raceway into the spindle recess.

Various other cooperator mechanisms, forming parts of the new combination, are present as will be more fully explained hereinafter; such mechanisms including particularly a novel spindle construction and spindle-driving connection adapted to afford simple means for permitting the spindle to pause when and for as long as required to permit operation of the thrusting means above mentioned, and also including means carried by the spindle for preventing loss of any hooks from the raceway during a driving and return operation of the spindle, as well as means, also preferably carried by the spindle, for holding a single hook set

exactly as provided in the receiving recess in the bottom of the spindle during the driving stroke of the latter.

Other objects and aims of the invention, 5 more or less broad than those stated above, together with the advantages inherent, will be in part obvious and in part specifically referred to in the course of the following description of the elements, combinations and 10 arrangements of parts and applications of principles constituting the invention; and the scope of protection contemplated will appear from the claims.

In the accompanying drawings, which are 15 to be taken as part of this specification, and in which I have shown merely a preferred form of embodiment of the invention:

Figure 1 is a front elevation thereof;

Figure 2 is a fragmentary view showing 20 certain of the parts of Figure 1 in vertical section;

Figure 3 is a similar view showing the driving spindle and the anvil, partially in side elevation and partially in section;

25 Figure 4 is an enlarged detail view, taken on the line 4—4 of Figure 1, showing the hooks held against exit from the raceway by the exterior of the plunger;

Figure 5 shows the parts of Figure 4, but 30 redisposed;

Figure 6 is a side elevation of the complete structure of Figure 1;

Figure 7 is an enlarged detail view, showing a portion of the raceway;

35 Figure 8 is a transverse section, taken on the line 8—8 of Figure 7;

Figure 9 is a detail view similar to Figure 5, but on a slightly reduced scale relative to the latter figure, and showing the cut-off or 40 thrusting means;

Figure 10 is a vertical section, taken on line 10—10 of Figure 9; and

Figure 11 is a perspective view, showing the parts of Figure 9.

45 Similar reference characters refer to similar parts throughout the several views of the drawings.

Referring to the details of the drawings, and particularly to Figures 1, 2 and 6, any 50 suitable support 1 may be provided for a head 2 having a main web 3, a lower extension 4 and an upper extension 5. Extension 4 adjustably mounts, in a cylindrical enlargement 6, a hook set or anvil 7; while extension 5 is shaped to guide a driving spindle 8, removably held in place by a plate 9.

This driving spindle is suitably recipro- 55 cated, as from a treadle not shown, by a link 10 connected to a lever 11 pivoted at 12 on lugs 13 on the top of head 2, incident to the provision of a pair of short links 13^a connecting the front end of lever 11 and the top of the spindle.

60 A bracket 14 on one side of the machine 65 carries a hook hopper 15, having a hinged

cover 16; and mounted to rotate within the hopper is a pick-up wheel 17 forming one of the important elements of the present invention due to its peculiar construction as hereinafter explained. This wheel is fixed 70 on a rotatable stud 18 between washers 19. The parts 17 and 18 are rotated intermittently with a ratchet 20 also fast on said stud. An arm 21 is fixedly carried by lever 11 and is connected by a link 22 to another arm 23 loose on stud 18, and this arm 23 pivotally carries a pawl 24 for rotating the ratchet. The parts are so designed that on each backward and forward movement of spindle 8 in a vertical direction, the ratchet, 80 which has eight teeth, is rotated one-eighth of a revolution; the pick-up wheel 17 of course having a corresponding fractional rotation through the collection of hooks in the bottom of the hopper, and in the direction 85 of the arrow shown in Figure 6.

Referring now to the peculiar construction of said pick-up wheel, it will be seen that the same has, in addition to the eight equidistant openings 25, a particularly novel structure in that each opening or pocket has a narrow elongate passage 26 opening thereinto at its inner end and open at its outer end at the periphery of the wheel, each such passage being established by an inwardly 90 directed finger 27. It will further be noted that each of such eight collections of elements 25, 26 and 27 is so designed that the curved wall of the generally pear-shaped pocket 25 near its inner portion of greatest width merges smoothly with the inner end of the wall of its passage 26 against which a hook or hooks 29 are to be transferred to hang therefrom by gravity when such hook approaches the location 29^a of Figure 6. 105 From that point on a hook then on the wheel cannot possibly be jarred or kicked loose irrespective of the vibratory shocks occurring.

Thus, in operation, the new pick-up wheel 110 may always be relied on to retain all its picked-up hooks which have been transported as far as the location 29^a, and to deliver all such hooks to the point 30 of Figure 6 and consequently to the hopper exit 31 of Figure 1, for delivery to the upper end of the gravity track or raceway 32. It will be understood that the shaping of the parts and the presence of fingers 27 insure this 115 important result, and thus one of the very serious defects in previous feeding mechanisms is absolutely overcome; as it will be appreciated that by the above described arrangement of parts and the hereinafter described cooperant mechanisms for insuring the transfer of one hook at a time from the lower end of the raceway, there will always be an adequate supply of hooks for such 120 transfer.

Said cooperant mechanisms include ele- 125

ments forming parts of the spindle 8 itself, and parts associated with the lower end of raceway 32, thereby to insure the transfer of one rivet at a time to the lower end of the 5 spindle at the end of each up-stroke of the spindle.

The parts last mentioned are operated from lever 11, by means of a secondary lever 33 having a forked upper end and actuated 10 by lever 11 through a stud 34 on the latter which lies within such fork. Lever 33 works through a wire or rod spring 35, bent as shown most clearly in Figure 6 to act also as a yieldable intermediary to prevent injury to the hook or machine on any inadvertent jamming of a hook or member 36 forming one of said parts at the lower end of the raceway. This member is secured to the lower end of spring 35, and is moved 15 back and forth, by a well-known kicking action of such spring, as the lever 33 rocks back and forth, thus causing the shaped outer nose of the member 36 to be intermittently retracted as shown in Figure 4 and 20 thrust to its outward limit of travel as shown in Figure 5, in timed relation to the up and down strokes of spindle 8.

This member 36, as shown best in Figures 9, 10 and 11, thus works back and forth 25 relative to a slotted way cut in a bracket 37; to that end said member being carried by a block 38 directly slidingly fitted in the way, below a suitable cover plate 37^a. Member 36 is really a lever, being pivoted at its inner 30 end at 39 within a longitudinal slot 40 formed in the upper surface of block 38. It will be noted that this slot is of greater width than member 36, and that said member is normally yieldably held to one side 35 of such slot as shown in Figures 9 and 10, by means of a leaf spring 41. Cover plate 37^a, which is held in place by screws 42, is provided with a slot 43 to accommodate the lower end of spring 35 in causing the 40 described movements of member 36.

Before any particularized description of the manner in which said member 36 works, it is in order to describe certain other parts 45 provided adjacent the lower end of raceway 32 and particularly the special and novel construction of spindle 8.

Referring particularly to Figures 3, 9 and 11, such spindle is made in two parts, the upper part 44 of which is tubular in its 50 lower portion. The lower spindle part is a separate piece 45, and the same has a reduced upper extension 46 fitting within the hollow portion of spindle part 44. These 55 parts 44 and 45 are yieldably held in the relation illustrated by means of a retractile coil spring 47 stretched between an eye at the upper end of the lower spindle piece and a cross-pin 48 in the upper spindle piece. The lower spindle piece is provided with a 60 keyway 49, kept by a keying screw 50, to

hold the spindle parts against relative rotation. The lower end of the lower spindle piece is cut out to provide a recess or pocket 51 to receive the head of a hook, and a plate 52 forms the bottom wall of such pocket to 70 lie between the jaws of the hook forming the head to prevent such hook from being crushed during the driving operation.

The operation of the parts just described, in combination with the member 36 and its 75 appurtenant devices, may now be given. It will be observed, most clearly perhaps from Figure 4, that the lower spindle piece 45 is so shaped and disposed relative to the lower end of raceway 32, that the same effectually 80 holds the column of sorted hooks in the raceway against egress therefrom after the spindle has received one of the hooks and while such spindle is thereafter descending for a driving operation relative to the last- 85 mentioned hook and until the spindle rises again sufficiently to bring its pocket 51 into alignment with the raceway as shown in Figure 1. On reaching such position, the spindle is automatically halted for a long 90 enough interval, but of course a very brief one, to permit a swift, sudden protrusion of the shaped nose of member 36 from the position shown in Figure 4 to that shown in Figure 5, and a return of said member. This 95 halting of the spindle, or rather of the lower piece 45 thereof, is brought about by the wall 52 acting as a stop relative to the underside of the raceway; while the telescopic relation of the two spindle pieces and the presence 100 of spring 47 permits this pausing of the pocket 51 to happen despite the operation of the lever 11 in consonance with the even speed of the driving shaft or the like carrying the treadle above mentioned. Also the 105 abnormal distention of the spring 47 insures that the stop means described will hold true to its appointed function. During the halting of the pocket 51 opposite the lower 110 jaw of the hooked head of the lowermost of the column sorted hooks at the bottom of raceway 32, and the simultaneous outthrust and retraction of the shaped nose of member 36, said nose engages the sleeve or hook proper of such lowermost hook and adds 115 the force of leaf-spring 41 to gravity acting on said hook and forcibly sweeps the hook into the spindle pocket, thus causing one hook to be surely transferred from raceway to pocket if the column of hooks in the raceway is too short to permit gravity to act alone for bringing about such transfer. At the same time the shaped nose of member 36 120 performs another very important function, because as the member noses in between the 125 hook being delivered to the pocket and the next adjoining hook in the column, member 36 holding the latter hook well back into the confines of the raceway and so prevents the latter from engaging any part of the pocket 130

- or the hook therein, to become injured or crushed and so to bring about the possible setting of an imperfect hook at the next driving operation. If the lacing hook as it is about to enter the pocket or set should stick for an instant as the member 36 is moving forward, the leaf spring 41 will allow the member to move away and not crush the hook before it enters the pocket.
- 10 In order to provide means for holding the single hook thus delivered to the spindle pocket set exactly as provided in the pocket during the driving stroke of the spindle, a lever 53 is pivotally mounted at 54 on the spindle as shown best in Figure 3, the lower end of this lever carrying a shaped foot for the purpose of engaging a facing concavity of the hook exterior as best illustrated in Figure 5; a spring 55 holding said foot in thrust toward the spindle pocket, except when as the upper end of the lever 53 is rocked to overcome the tension of spring 55, which rocking movement occurs at the upper end of each stroke of the spindle, due 20 to the upper end of said lever engaging the cammed surface of a fixed plate 56, all as shown most clearly in Figure 6.
- 25 Inasmuch as many changes could be made in the above construction and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features 40 of the invention herein described and all statements of the invention which, as a matter of language, might be said to fall therebetween.

I claim:

- 45 1. In a lacing hook setting machine, a two-part driving spindle, the lower part of said spindle being mounted for telescoping movement relative to the upper part during each hook setting operation and having a recess for receiving a part of a lacing hook to be set, and means for feeding hooks to said recess.
- 50 2. In a lacing hook setting machine, a two-part driving spindle, the lower part of said spindle being resiliently and telescopically related to the upper part and having a recess for receiving a part of a lacing hook, and means for feeding hooks to said recess.
- 55 3. In a lacing hook setting machine, a two-part driving spindle, the lower part of said spindle being mounted for telescoping movement relative to the upper part during each hook setting operation and having a recess for receiving a part of a lacing hook,

a raceway for feeding hooks to said recess, and a stop carried by the lower part of said spindle adapted for engagement with the raceway.

4. In a lacing hook setting machine, a 70 driving spindle, a bit telescopically related to said spindle, and mounted for telescopic movement relative to the spindle during each hook setting operation, said bit having a recess for receiving part of a lacing hook, 75 a raceway for feeding hooks to said recess, and a stop carried by said bit adapted for engagement with the raceway to arrest the motion of the bit while the spindle continues its upward movement.

5. In a lacing hook setting machine, a 80 driving spindle, a bit resiliently and telescopically related to said spindle, said bit having a recess for receiving part of a lacing hook, a raceway for feeding hooks to said recess, and a stop carried by said bit adapted for engagement with the raceway to arrest the motion of the bit while the spindle continues its upward movement.

6. In a lacing hook setting machine, a 90 gravity raceway for guiding and feeding a column of sorted hooks, a driving spindle including a bit having a hook-receiving recess at its driving end, such recess having an opening adapted to assume a hook-receiving position adjacent to the exit of the raceway when the bit is retracted a certain distance, a stop means for holding the bit when thus retracted, operating means for reciprocating said spindle, said spindle always 100 engaging said bit above the recess to reciprocate the bit with the spindle at each driving stroke, and means permitting the spindle to move relative to the bit during each retraction stroke when the stop means functions to hold the bit as mentioned, said bit and spindle being coupled in telescopic relation with a retractile spring tending to force said bit and spindle together during the entire retracting stroke of said spindle.

110 7. In a lacing hook setting machine, a driving member having a hook-receiving recess, a raceway for feeding hooks to said recess, a slide member, a groove in the slide, a picker mounted on a pivot pin in the groove, and a spring mounted in the groove to normally press the picker against one side of the groove so that it travels in a straight line, but permitting lateral yielding of the picker should a rivet become 115 jammed in the raceway.

8. In a lacing hook machine, a driving member having a hook-receiving recess, a raceway for feeding hooks to said recess, a reciprocatory member, and a picker pivotally mounted on said member provided with a beveled nose for engaging and pushing a hook into said recess.

In testimony whereof I affix my signature.
EDWIN B. STIMPSON.
